[57] **CLAIM**

The ornamental design for a cover plate for an RF identification reader, as shown and described.

DESCRIPTION

FIG. 1 is a front perspective view of the cover plate for an RF identification reader according to a presently preferred embodiment of the present invention;

FIG. 2 is a top plan view of the cover plate for an RF identification reader of FIG. 1;

FIG. 3 is a bottom plan view of the cover plate for an RF identification reader of FIG. 1;

FIG. 4 is a right side elevational view of the cover plate for an RF identification reader of FIG. 1, the left side elevational view being a mirror image thereof; and,

FIG. 5 is a front elevational view of the cover plate for an RF identification reader of FIG. 1, the rear elevational view being a mirror image thereof.
